UNITED STATES PATENT OFFICE.

IRONE H. RUSSELL, OF WASHINGTON, DISTRICT OF COLUMBIA.

AMBULANCE.

982,997.

Specification of Letters Patent. Patented Jan. 31, 1911.

Application filed November 18, 1909. Serial No. 528,826.

To all whom it may concern:

Be it known that I, IRONE H. RUSSELL, a citizen of the United States, residing at Washington, in the District of Columbia, have invented certain new and useful Improvements in Ambulances; and I do hereby declare the following to be a full, clear, and exact description of the invention, such as will enable others skilled in the art to which it appertains to make and use the same.

My present invention is an improved ambulance for use in conveying injured persons from place to place.

In the accompanying drawing, I have shown the best form in which I have contemplated embodying my invention and my said invention is disclosed in the following description and claims.

In the drawing, Figure 1 is a perspective elevation of my improved ambulance. Fig. 2 is a view of the supporting frame work removed from the wheels for hospital or other uses.

In the said drawing, A is the floor of the ambulance of substantial thickness and material.

A', A' are the sides of the main body, connected to the bottom in a substantial manner.

To the bottom near the rear and front ends are firmly secured the sockets a, a, a, a. These sockets extend upward from a substantial base plate a' and a strengthening flange a² is provided extending inwardly from the socket a. The base plate of the sockets extends inwardly and to the ends of the socket, such base plate having its outer side adapted to fit against the side of the main body and bring the socket against the same.

In the sockets a, a, a, a are mounted four vertical standards b, b, b, b. These are preferably of tubes to make the structure as light as possible.

The pair of standards at the rear of the ambulance are connected by a bar c and those at the front are similarly connected by a bar c', and the two connecting bars are also connected by a bar extending longitudinally of the ambulance from the center of the cross bar c to the cross bar c'. All of these parts are also made as light as possible consistent with the securing of the necessary strength.

On the bottom of the ambulance are placed two narrow mattresses B, B. These mattresses have one side lying against the

sides of the main body, and are recessed or divided to accommodate the flanges a², the mattress on each side of the brace being thicker than the flange to prevent any part of the body of the injured person placed thereon, from coming in contact with the brace.

At a suitable distance above the floor of the ambulance each of the standards a, a, a, a are provided with collars or sleeves d, d, d, d and above these at about the same distance from the collars d, d, d, d that the latter are from the floor of the ambulance, are placed sleeves or collars e, e, e, e and collars f, f, f, f are placed close to the top of the standards at a like distance above the collars or sleeves e, e, e, e. These collars are firmly secured to the standard in any preferred manner. I prefer to secure them by rivets or by bolts passing through them into the standards.

Each of the collars or sleeves d, d, d, d is provided with an inwardly extending hooked support d', while the collars or sleeves e, e, e, e are provided with a like support and have strongly pivoted thereto the curved supporting bars e', e', e', e'. The outer or free end of the bars is each provided on its inner or concave side with a hook e² and the cross bars e, e' are provided with hooks c², c², c², c² to readily engage these hooked supporting bars and hold them in an elevated position out of the way, when not in use.

To each of the sleeves or collars f, f, f, f is pivoted a like curved hooked supporting bar f', f', f', f' and the cross bars are provided with suitably disposed hooks c³, c³, c³, c³ to support these when not in use. The bars e', e', e', e' and f', f', f', f' are pivoted on opposite sides of the standards to which they are attached and the hooks c² and c³ are oppositely disposed to accommodate this arrangement. These hook bars are given the upwardly curved form in order to give greater space beneath them for the accommodation of the injured person and facilitate access to such person.

The upper part of the frame formed by standards and associated parts, is to be covered with canvas or a preferred water proof material.

This form of ambulance is constructed for use in connection with the stretcher shown in my former Patent No. 910,728, and a compartment B' is formed below the body of the ambulance or below the axles of the

same for carrying such number of them as can be used in the ambulance.

In the use of the ambulance, the first injured persons are laid upon the mattresses 5 on the floor of the vehicle. If further accommodation is desired, a stretcher with the injured person is lifted in and one side of the stretcher is placed in the hooked support d' on one side of the vehicle. The 10 supporting bars e', e' on the same side are detached and hooked under the opposite side of the stretcher, as shown at the left in the figure of the drawing. The ambulance is preferably made of such length that the 15 hooked supports will engage the sides of said stretcher between the ends of the stretcher and the cross bars of the same so that all endwise movement of the stretcher will be prevented.

20 The body of the vehicle will preferably be supported by springs and the construction of such springs and the running gear of the vehicle will be such that the body will not be raised high between the wheels.

25 It is to be noted that when the mattresses or beds on the bottom only are occupied, the space above them is unoccupied and free from obstructions, until a stretcher is placed above them, and when such a stretcher has 30 been so placed the space above the latter is also clear until a further stretcher has been placed above it. By this means I provide for the easy and ready placing of the stretchers in position and also provide for free access to such injured as may be placed in 35 the ambulance.

The main body of the vehicle is closed by an end board of any preferred construction.

If it is desired to carry persons in a sitting 40 posture, one or two stretchers can be placed in position to serve as seats.

The supporting frame work is shown in Fig. 2 as removed from the ambulance running gear. In this condition it can be used 45 for many purposes. At the right in this figure, I have shown the frame as supported on a flooring, while at the left it is shown as placed on the ground. When resting directly on the ground, the mattresses need not 50 necessarily be used. They could be used if

the frame work were placed on a platform or flooring. In this way my supporting frame may be used for various temporary purposes, for hospital, temporary barracks and sleeping accommodations for tuberculosis patients and the like uses. 55

What I claim and desire to secure by Letters Patent is:—

1. In an ambulance, the combination with the main body, of the standards and parts 60 connecting the upper ends of the same and a pair of mattresses on the floor of the said main body, the said standards being provided with rigid supports for the outer side of one or more stretchers and curved bars 65 pivoted at one end to said standards and having at the opposite end a hook to detachably engage and support the opposite side of a stretcher.

2. In an ambulance, the combination with 70 the main body, of the standards and parts connecting the upper ends of the same, a pair of mattresses on the floor of the said main body, rigid supports for the outer sides of one or more stretchers on said standards 75 above said mattresses, pivoted hook bars for supporting the inner sides of said stretchers and hooks for supporting the pivoted hook bars, out of operative position.

3. In an ambulance, the combination with 80 the main body, of standards secured to the floor of the said main body and parts connecting the upper ends of the same, rigid supports secured to said standards for supporting the outer sides of one or more 85 stretchers on each side of the ambulance, curved hook bars pivoted to said standards to support the inner sides of said stretchers, and hooks secured to the parts connecting the upper ends of said standards for receiving and holding the said pivoted hook bars 90 out of operative position, said pivoted hook bars being pivoted alternately on opposite sides of the standards.

In testimony whereof I affix my signature, 95 in the presence of two witnesses.

IRONE H. RUSSELL.
